CLAIM

The ornamental design of a front panel for a measurement instrument, as shown and described.

DESCRIPTION

FIG. 1 is a perspective view of a front panel for a measurement instrument, the phantom lines not being a part of the invention;

FIG. 2 is a front elevation view of the front panel for a measurement instrument;

FIG. 3 is a top plan view of the front panel for a measurement instrument;

FIG. 4 is a bottom plan view of the front panel for a measurement instrument;

FIG. 5 is a left side elevation view of the front panel for a measurement instrument; and,

FIG. 6 is a right side elevation view of the front panel for a measurement instrument.

The broken line showing of a measurement instrument is for illustrative purposes only and forms no part of the claimed design.
